UNITED STATES PATENT OFFICE.

EDWARD MALLINCKRODT, JR., OF ST. LOUIS, MISSOURI, ASSIGNOR TO MALLINCKRODT CHEMICAL WORKS, OF ST. LOUIS, MISSOURI, A CORPORATION OF MISSOURI.

METHOD OF PURIFYING AND PACKAGING ETHER.

Application filed March 18, 1921. Serial No. 453,285.

To all whom it may concern:

Be it known that I, EDWARD MALLINCKRODT, Jr., a citizen of the United States, residing at the city of St. Louis and State 5 of Missouri, have invented a new and useful Method of Purifying and Packaging Ether, of which the following is a specification.

The object of this invention is to provide 10 a novel and effective method, or plan of procedure, for purifying and packaging the highest grade of ether for anesthesia and other purposes where absolute freedom from the slightest tendency to alteration in storage is desirable. To attain this end it is 15 necessary to produce ether free from oxygen and to package the same without the access of air. The invention, therefore, relates to a method of producing and packaging 20 air-free ether in hermetically sealed cans without the access of air.

My invention may be practiced by use of any appropriate means or apparatus for excluding air from the containers in which 25 the ether is to be placed, and by placing the air-free purified ether in the containers while the air is excluded from both the containers and the ether, and then hermetically closing and sealing the containers 30 so that the air will be permanently excluded therefrom.

In the accompanying drawings—

Fig. 1 is a view, diagrammatic in nature, 35 of an apparatus for practicing the invention.

Fig. 2 is a sectional view showing an appropriate arrangement of the device for applying a cap or closure to the can or container in which the air-free purified ether 40 is to be packaged.

Fig. 3 is a view showing an appropriate arrangement for securing the cap or closure to the container.

The apparatus which is shown is one 45 form of usable apparatus for practicing the invention, though it will be understood that the invention may be practiced in any other form of apparatus capable of use to obtain the desired results. Accordingly, in describing generally the illustrated apparatus, I do not, to any extent, restrict or confine myself to the use of any definite or specific type of mechanism or apparatus.

As shown, the distillation column is provided 50 with proper equipment of dephlegma-

tor and condenser, and is set up in such a manner that when a supply of ether is continuously fed in toward the middle of the column, the air-free purified ether flows from the bottom of the column into an air-free storage tank while the condenser is arranged to allow the escape of air and the removal of a small amount of impure ether. The ether may be fed into the distillation column continuously through an inlet pipe 60 communicating with an elevated ether storage tank (provided with a float box equipment for maintaining a constant level), or in gaseous form from the stills in which it is manufactured, the essential 65 feature being that the ether be subjected to a distillation or boiling out process in the distillation column in order to obtain an air-free purified condition of the ether.

The ether is prevented from leaving the 70 distillation column by the familiar action of the dephlegmator, which is similar to those employed in the distillation industry. The result is that the ether vapors are condensed and a downward flow of liquid 75 over the trays in the distillation column is produced. The air does not dissolve in the hot liquid and is carried out and eliminated by that portion of the vapors which pass into the condenser. By the time the 80 main flow of ether has passed to the bottom of the distillation column it is free from air.

From the distillation column, the ether passes through an outlet pipe leading to a 85 purified ether storage tank which is provided with a gasometer. The entire apparatus is filled with pure nitrogen or other suitable protecting gas free of oxygen.

From the purified ether storage tank the 90 ether is delivered in the purified air-free condition into the cans or containers inside a filling box from which the air has been displaced by pure nitrogen or other suitable protecting gas. The caps or closures are 95 then placed on the cans and are securely crimped to the cans to seal them hermetically. The cans may be delivered into the filling box from a reservoir 1 which is equipped with valves 2 and 3 to form a 100 reservoir between them. The reservoir 1 is in the form of a pipe opening into the filling box and the can reservoir is located between the valves 2 and 3. The air is exhausted from the reservoir 1 through a 105

110

pipe 4 in connection with the vacuum pumps. After the air has been exhausted from the reservoir 1 and from the cans contained therein, the pipe 4 from the vacuum pump 5 to the reservoir 1 is closed by a valve 5, after which the pure nitrogen, or other suitable gas free of oxygen, is let into the reservoir 1 through a valve controlled pipe 6 communicating with the gasometer. Owing 10 to the fact that pumps working to a very high vacuum are difficult to maintain in operative condition, an ordinary vacuum pump is used and the air in the reservoir 1 is reduced to a satisfactory minimum by exhausting the air therefrom, and breaking the vacuum with nitrogen, and repeating the operation several times. The gasometer is also in communication with the filling box through a pipe 7, so that said filling box 15 is kept filled with the gas which is free of oxygen, it being understood that the filling box is free of air so that when the cans are delivered into the filling box they remain free of air.

20 25 The cans having been dropped into the filling box from the reservoir 1 are now successively moved by hand as hereinabove stated, or otherwise as desired, to the various positions of filling, capping, etc., during all 30 of which operations, the air is excluded from the filling box and therefore from the cans and from the ether that is placed in the cans. The cans are first filled with ether by means of a simple measuring apparatus seen at 8 35 in the pipe leading from the purified ether storage tank into the filling box and arranged to discharge the required amount into the cans as they are moved successively into filling position A.

40 45 Next the cans are moved from position A to position B, in which caps or closures are applied to the cans successively by a manually operated suction tube 9 extending through one wall of the filling box and being operative for the purpose of applying these caps or closures to the cans. After the caps or closures have been applied to the cans, the cans are moved successively to a 50 position C in which the closure fastening means 10 operates to crimp or secure the caps or air tight closures to the cans. Instead of a mechanical device such as illustrated at 10, the caps or closures may be soldered on while the cans are in the filling box. Such manipulation may be effected, if desired, by means of an appropriate 55 soldering device, and by enclosing the hand in a rubber glove 11 having its sleeve portion hermetically connected with the wall of the 60 filling box around a suitable opening to permit the hand to be passed into the glove to operate the soldering device. The cans may also be moved to the various positions of filling, capping, etc., by use of the hand in 65 the glove 11, the elasticity and flexibility of

which permit the necessary movements of the hand. The suction tube 9, as shown in Fig. 2, is mounted in a universal bearing joint to permit freedom of movement in every direction. As stated, the tube 9 is a 70 suction tube and the caps may be picked up successively by touching the end of the tube to the caps contained in any support holding them. After a cap has been applied to the end of the suction tube 9, said tube is 75 operated to deposit the cap on the nozzle of the can.

Next the air-tight sealed can is discharged from the filling box through a seal which keeps out the outside air such, for instance 80 as a water seal as shown.

Observation of the interior of the filling box may be obtained through a glass window 12 forming a part of one wall of such box and the interior of the filling box may be 85 illuminated as by a lamp 13.

It is, of course, apparent that my invention is in no way dependent upon the specific mechanisms shown; it being only essential that the filling box and the cans be freed 90 from air and refilled with the protecting gas and that the ether also be free from air during the filling and sealing operations. No specific mechanism is shown for moving the cans to their various positions in the 95 filling box, since it is obvious that their movement may be effected manually or mechanically.

From the foregoing it is apparent that my invention is complete in that it provides 100 an efficient and comparatively simple method or plan of procedure for sealing air-free purified ether hermetically in air-free cans or containers, and this result is obtained by filling the cans with ether in a filling box or 105 receptacle from which the air has been excluded and from which the air remains excluded during the entire operation. I do not restrict myself to unessential features of the invention, or to the specific way and arrangement shown, except as set forth in the appended claims.

What I claim and desire to secure by Letters Patent, is:—

1. The method of packaging ether in containers, which consists in placing the containers in a substantial vacuum; passing the containers from the substantial vacuum into a filling box; filling the containers with ether; and hermetically closing the containers and maintaining an atmosphere of gas containing no free oxygen in the box during the filling and closing steps. 115 120

2. The method of preparing and packaging ether which consists in establishing a 125 vacuum about and within the containers, then establishing an atmosphere of gas containing no free oxygen, then removing all air from a body of ether, filling the containers with the air-free ether, hermetically 130

closing the containers and maintaining the atmosphere of gas containing no free oxygen during the filling and closing steps.

3. The method of preparing and packaging ether which consists in placing containers in a closed chamber, exhausting the air from the chamber, removing the containers to a second chamber, removing all air from a body of ether, filling the containers with the air-free ether, hermetically closing the containers and maintaining an atmosphere of gas containing no free oxygen in the second chamber during the filling and closing steps.

15 4. The method which consists in establishing a vacuum about and within containers to be filled with ether, then establishing an atmosphere of gas containing no free oxygen about and within said containers, filling 20 said containers with ether and sealing said containers and maintaining the atmosphere of gas containing no free oxygen about said containers during the filling and closing steps.

25 5. The method which consists in removing the air from about and within containers to be filled with ether, then establishing an atmosphere of gas containing no free oxygen

about and within said containers, filling said containers with ether and sealing said containers, and maintaining the atmosphere of gas containing no free oxygen about said containers during the filling and closing steps.

30 6. The method which consists in establishing a vacuum about and within containers to be filled with ether, then establishing an atmosphere of gas containing no free oxygen about and within said containers, filling said containers with air-free ether and sealing 40 said containers and maintaining the atmosphere of gas containing no free oxygen about said containers during the filling and closing steps.

35 7. The method which consists in removing the air from about and within containers to be filled with ether, then establishing an atmosphere of gas containing no free oxygen about and within said containers, filling 50 said containers with air-free ether and sealing said containers and maintaining the atmosphere of gas containing no free oxygen about said containers during the filling and closing steps.

EDWARD MALLINCKRODT, JR.
